M. C. LOESCH

VAPORIZER FOR COMBUSTION ENGINES

Filed April 28, 1920

Wilton C. Loesch Inventor
By *Walter F. Murray* Attorney

UNITED STATES PATENT OFFICE.

MILTON C. LOESCH, OF CINCINNATI, OHIO, ASSIGNOR OF ONE-HALF TO WILLIAM F. RYAN, OF CINCINNATI, OHIO.

VAPORIZER FOR COMBUSTION ENGINES.

Application filed April 28, 1920. Serial No. 377,297.

To all whom it may concern:

Be it known that I, MILTON C. LOESCH, a citizen of the United States of America, and a resident of Cincinnati, in the county of 5 Hamilton and State of Ohio, have invented a new and useful Improvement in Vaporizers for Combustion Engines, of which the following is a specification.

An object of my invention is to provide a 10 vaporizer that may be inserted between the intake manifold of an automobile engine and the supply pipe leading from the carburetor to the intake manifold.

Another object is to provide a device for 15 the purpose stated that will be cheap, simple and efficient, and that may be easily attached.

These and other objects are attained by 20 means described herein and disclosed in the accompanying drawing in which:

Fig. 1 is a front elevation of a vaporizer embodying my invention mounted between the supply pipe and an intake manifold.

Fig. 2, is an enlarged view of line 2—2 of 25 Fig. 1.

Fig. 3, is an enlarged end view of a device embodying my invention, parts being broken away.

My invention comprises the blocks A and 30 A' between which is supported an electrical heating element B. The blocks are adapted to be mounted between the intake manifold C and the supply pipe D.

The blocks A and A' have central perfora-

tions a. Centrally between the blocks is 35 formed a seat a' in which is seated the frame b of the heating element. The blocks are preferably made of fibre or some other similar electrically insulating material. A wire b' is wound about frame b and comprises the 40 heating element. This wire is electrically insulated, preferably with a cotton covering. The ends of the wire are connected to the binding posts b² and b³ on the outer surface of the blocks. The gaskets a² are formed 45 upon the blocks whereby the vaporizer may be secured between the pipe C and D.

The operation of the device is as follows:

An electrical current is passed thru the wire b' upon the frame b, thereby forming 50 a heated obstruction against which the fuel coming from the carburetor impinges, thereby breaking up the globules of fuel oil into very fine particles. The breaking up of these globules assures a more uniform mixture 55 of the gas entering the engine chamber, resulting in increased efficiency and mileage per unit of fuel oil.

What I claim is:

A device of the class described comprising 60 an electrical heating element, means to mount the heating element transversely of the bore of an intake manifold, and a heat radiating, fluid absorbing, electrically insulating cover for the heating element. 65

In witness whereof, I have hereunto set my signature this 26th day of April, 1920.

MILTON C. LOESCH.
